UNITED STATES PATENT OFFICE.

CHARLES E. TITCHENER, OF BINGHAMTON, NEW YORK.

VEHICLE-TOP.

1,172,643.

Specification of Letters Patent.

Patented Feb. 22, 1916.

Application filed February 26, 1915. Serial No. 10,822.

To all whom it may concern:

Be it known that I, CHARLES E. TITCHENER, a citizen of the United States, residing at Binghamton, in the county of Broome 5 and State of New York, have invented certain new and useful Improvements in Vehicle-Tops, of which the following is a specification.

This invention relates to vehicle tops.

10 The present invention relates to that general class of vehicle tops commonly known as "one-man tops," the construction being such that a single person may fold or extend the top without assistance. Tops of this 15 class are particularly adapted for use on automobiles, as they render unnecessary the use of supporting bows at the sides of the front seat of the car.

20 My object is to provide an improved one-man top, or bow socket construction for one-man tops, which will fold in compact condition in relation to the rear bow sockets; will be very stiff when extended so as to have a maximum rigidity and may be 25 quickly and easily extended or folded.

The present invention consists, first, of a 30 double or trussed link or lever and its novel combination with forwardly and upwardly extending bow sockets; more specifically in the provision of a stop in the construction just recited, which coöperates with the short 35 upwardly extending bow socket to assist in maintaining the long or extension bow or bow socket in its proper position; second, in spring means combined with the structure 40 adapted to act as a balancing spring to make it easier to fold or put up the top; and third, an improved combination of bow sockets, struts, spring lever and stop, mutually co- operating to provide an improved one-man top construction.

In the accompanying drawings: Figure 1 is a side elevation showing the top up; Fig. 2, a detail side view showing the invention 45 folded; Fig. 3, a detail showing the slot in the main brace or strut; Fig. 4, a similar view showing the slot of the supplemental brace or strut; Fig. 5, a detail perspective showing the double construction of the lever 50 and the way in which the short bow socket is pivoted thereto; and Figs. 6 and 7, detail views of modifications.

The main or upright bow socket 1 may be

of any usual or preferred arrangement and construction. The long, forward, or extension bow socket is shown at 2 and the short or second bow socket at 3. The bow socket 2, instead of being directly connected to bow socket 1, is connected thereto by a lever or link 4 which is composed of two parts, making it double and of trussed construction (Fig. 5) which is very rigid and prevents swaying or displacement of the top when extended. The link or lever 4 is pivoted at 5, preferably by a rivet, to the bracket or iron 6 which is secured to the bow socket 1, the bracket 6 being preferably provided with a lug 7 for this purpose. The rear end of the bow socket 2 and the forward end of the double link or lever 4 are curved or offset upwardly as at 8 and are pivoted together, as by a rivet, at 9, the solid, rear end of the bow socket 2 being received between the parts of the double link 4. The upwardly extending parts 8 dispose the pivotal point 9 upwardly from the line of pivots, as will presently appear, thus rendering it possible to easily "break" said joint and fold the top, while also practically preventing accidental breaking of this joint. The lower, solid end of the bow socket 3 is flattened as at 10, and is received between the members of the double link 4 and pivoted as by a rivet thereto at 11. A stop 11^a which may be a rivet, bridges the links 4 and serves as a rest for the solid part 10 when the top is extended, thereby holding the extension bow socket 2 in its proper position and affording rigidity, in view of the construction and arrangement of the braces 90 or struts and because the trussed link will not flex or bend in any direction. I employ double supporting braces consisting of a main brace 12 and a supplemental brace 13. The main brace 12 is pivoted, as by a rivet, 95 to the solid portion 8 of the extension bow socket 2 at 14. The rear end of the main brace 12 is pivoted by a slot-and-pin connection 15 to a lug 16 on the bracket 6. This main brace serves as a main support for the top and the supplemental brace 13 has a supplemental support. The supplemental brace 13 is pivoted to the bow socket 3 at 17 and at its forward end has a slot-and-pin connection 18 with the extension bow socket 100 2. Now, as the portion 10 of the bow socket

3 is arrested by, and rests on the stop 11^a, when the top is up, the bow socket 3 is held rigidly and sustains the extension bow socket 2 through the link 13. At the same time the double link 4 and bow sockets 3 and 2 are sustained in extended position by the main brace 12. The slot-and-pin connections 15 and 18 afford the requisite play to permit movement of the parts when the 10 top is extended or closed.

It will be observed that the pivots 5, 11, 14 and 18 are in a substantially straight line when the top is extended or up. This, in connection with the bracing and supporting 15 action of the braces 12 and 13, affords great rigidity.

As thus far described, the invention is complete and operative and I claim it as such, but I have found that the top may be 20 raised and lowered with greater ease if a spring, such as shown at 19, be employed. This spring is of the contractile coil type whose upper end is anchored to the bracket 6, as for instance, by engagement with the 25 pivot pin 15 and whose lower end engages a stud 20 at a suitable point on the link 4. This spring acts as a balancing spring which, by its contraction, assists in the raising of the top, and, by its contractile tendency by 30 offering a certain resistance to the folding of the top, prevents too sudden collapse thereof. At the same time, however, the spring is so arranged that when the parts are folded, as shown in Fig. 2, the pull of 35 the spring is through the pivot 5, and consequently, the spring does not snap the parts upwardly or materially assist in extending the top until the latter has been started by manual operation from the folded position 40 of Fig. 2.

A locking pin or stud 21 projecting freely from the inside of one part of the double link 4, and an eye-bracket 22 on the bow socket 1 which is adapted to enter in between the parts of link 4 and receive said stud, provide means for locking the parts in collapsed position, as shown in Fig. 2.

In Fig. 6, I have shown a modification wherein the main brace or strut 12^a is upwardly inclined and pivoted at 6^a to bow 1 below the lever 4. The bow socket 3^a is not pivoted to lever 4, but is pivoted at 11^b to strut or brace 12^a. Strut or brace 13 is pivoted to bow socket 2 and bow socket 3^a.

55. In the modification shown in Fig. 7, the main brace or strut is entirely dispensed with. In this form, the short bow socket 3, brace 13, lever 4 and bow socket 2 are all arranged and connected as in the form 60 shown in Fig. 1. The fabric 25 of the top assists in sustaining the parts and while the structure is not as rigid as that of Fig. 1, it is a practical one.

Having thus described my invention; what

I claim as new and desire to secure by Letters Patent, is:

1. In a vehicle top, the combination with a double or trussed pivoted link or lever comprising connected members arranged side by side, of a forwardly extending bow 70 socket or member pivoted to said link or lever, an upwardly extending bow socket or member pivoted to the double or trussed link or lever in between the parts thereof, and a stop support or rest for engaging the upwardly extending bow socket or member with the double or trussed link or lever. 75

2. In a vehicle top, the combination with a pivoted link or lever, of a forwardly extending bow socket or member pivoted to 80 said link or lever, an upwardly extending bow socket or member pivoted to the link or lever, a double supporting brace or strut comprising two independent braces, one of which is pivoted to the extension bow socket or member and the other being pivoted to the upwardly extending bow socket or member and to the forwardly extending bow socket or member, and a spring coöperating 85 with the link or lever adapted to lift the said link or lever and thereby assist in the extension of the aforesaid parts. 90

3. In a vehicle top, the combination with an upwardly extending foldable main bow socket, of a foldable extension top support comprising a link or lever pivoted to the aforesaid bow socket, a forwardly extending or extension bow socket pivoted to the link or lever, a main brace or strut pivoted to the forwardly extending bow socket 95 and also to the upwardly extending bow socket aforesaid, an upwardly extending foldable bow socket pivoted to the link or lever, a supplemental brace or strut pivoted to the upwardly extending bow socket, 100 last-named and also to the forwardly extending bow socket, means for supporting the upwardly extending bow socket from the link or lever, and a balancing contractile coil spring connected to the link or lever and the main bow socket, said parts being so arranged that the main and supplemental braces sustain the extension top support aforesaid when the parts are raised and said parts being adapted to fold or collapse 110 alongside of the main bow socket. 115

4. In a vehicle top, the combination with a main bow socket, of a top support comprising a double or trussed link or lever pivoted to the main bow socket, and a latch 120 comprising an eye-bracket on the main bow socket adapted to enter the space between the parts of the double link, and a pin carried on the inside of said double link adapted to enter said eye-bracket. 125

5. In a vehicle top, the combination with main upright bow sockets or members having brackets provided with lugs, of for-

wardly extending double trussed links or levers, each comprising a pair of connected members arranged side by side constituting a rigid strut adapted to resist lateral flexing, 5 swaying and displacement, the members of each pair of links or levers being pivoted to the respective lugs on opposite sides thereof, and a bow having its ends jointed to the respective double trussed links or levers be-

tween the members thereof and constituting 10 a forward extension of said trussed links or levers.

In testimony whereof I affix my signature in presence of two witnesses.

CHARLES E. TITCHENER.
